DUMPING VEHICLE

Application filed October 9, 1923. Serial No. 667,445.

The present invention relates to dumping vehicles and more particularly to elevating or hoisting devices for dumping vehicles.

The object of the invention is to provide 5 a dumping vehicle of simple and rugged construction, the body of which can be elevated in an efficient manner from the beginning to the end of the hoist without placing undue stresses on any parts of the mechanism.

10 With this object in view the invention consists of certain novel features of construction, combinations and arrangements of parts hereinafter described and particularly defined in the claims.

15 In the accompanying drawings illustrating the preferred form of the invention Fig. 1 is a side elevation of the body and frame of the improved dumping vehicle; Fig. 2 is a detail plan view of one of the hoisting arms 20 and adjacent parts; and Fig. 3 is a section on line 3—3 of Fig. 1.

The illustrated embodiment of the invention comprises a body 5 having a floor 6 supported upon the I-beams 8, the body being pivoted at 10 to the frame 12 of the vehicle at its rear end. The elevating is effected through a pair of hoisting arms, one of which is indicated generally at 14, the other being disposed in a similar position at the other side 25 of the vehicle. As viewed in side elevation the hoisting arm 14 is provided with a long horizontal portion and an upwardly inclined portion at the rear, the rear end being pivoted upon a cross rod 16 which passes through the floor beam 8 and extends transversely under the body to the other side. The forward end of the hoisting arm 14 takes against a stop 20 depending from the floor 6 of the body. As viewed in Fig. 2, the hoisting arm 14 presents in plan a yoke-shaped appearance, consisting of a single piece of metal bent to form 35 side plates 22 and 23 connected by the U-shaped forward end 24, the plates being separated by a spacer sleeve 25 on the rod 16. The hoisting arm is attached to a cable 26 by means of an eye bolt 28 secured in the forward end of the arm, the cable being fastened 45 at its other end to a driving shaft 30 which is journaled in brackets 32 attached to the frame 12. The driving shaft 30 is rotated in any

usual or preferred manner, as by hand or from the vehicle engine, to wind up the cable and exert an endwise pull upon the hoisting arms to lift the body to the position indicated at A in dot and dash lines.

55 Inasmuch as the initial pull on the hoisting arms is not in such a direction as to lift the body directly upward, it is desirable to provide additional means for giving the body a direct upward thrust until the parts have assumed such a position that the pull upon the arms through the cable is made effective for continuing the motion of the body. To this end the driving shaft 30 is provided at each 60 end with a pair of cams 34 bearing against an anti-friction roller 36 mounted between the side plates of the hoisting arm, such that upon the first rotation of the driving shaft the cam pushes upwardly on the hoisting arms, the cable being meanwhile wound up on the driving shaft to move the body into the position 65 shown at B in dash lines. After the cams have lifted the body as far as they are able, the hoisting arm and the body are arranged at a sufficient angle with respect to each other 70 so that continued winding of the cable imparts a thrust upon the body in the desired direction of motion, thus lifting the body ultimately to position A, the cams meanwhile 75 rotating between the side plates of the hoisting arm by virtue of their narrower spacing, as shown in Fig. 3. The cable is preferably wound on the underside of the driving shaft, as indicated in Fig. 1, so as to exert a sufficient initial downward 80 component of force upon the forward end of the hoisting arm to cause the arm to act as a lever with its fulcrum on the cams 34 to give an upward thrust to the body, augmenting 85 the upward thrust attained by the cams themselves.

90 It will be seen that the present invention provides a construction by which an initial upward thrust may be readily given to the body so as to place the parts in such position 95 that the continuation of the lift may be most readily accomplished. Furthermore, the hoisting arms may be constructed so as to resist only longitudinal stresses. The cams on the driving shaft serve to confine the 100

cable winding so that the pull on the hoisting arms is always substantially longitudinal, there being no appreciable lateral stress by virtue of the restricted space in which the cable is wound on the shaft. The cable may also wind in several layers on the shaft, thereby increasing the effective diameter of the winding drum as the hoisting proceeds so that the final operation of the hoist, when the hoisting arms are in their most effective position, may be carried out at somewhat greater speed than the initial portion of the hoist.

The nature and scope of the invention having been indicated and a mechanism embodying the invention having been specifically described, what is claimed is:—

1. A dumping vehicle having, in combination, a dumping body, a pair of normally horizontal hoisting arms for the body, a shaft, connections from the shaft to the hoisting arms for lifting the body upon rotation of the shaft, and cams carried by the shaft and engaging with the hoisting arms for giving an initial upward thrust to the body.

2. A dumping vehicle having, in combination, a dumping body, hoisting arms for the body each consisting of a pair of spaced side plates, a shaft, cable connections from the shaft to each hoisting arm and initially disposed between the side plates thereof for exerting a pull on the hoisting arms when the shaft is rotated, and means for confining the cable as it is wound on the shaft in a plane between the planes of the side plates whereby lateral stresses on the hoisting arms are substantially eliminated.

3. A dumping vehicle having, in combination, a dumping body, hoisting arms pivoted to the body, a shaft, cable connections from the shaft to the hoisting arms adapted to exert a substantially longitudinal pull on the hoisting arms when the shaft is rotated, a pair of cams engaging each hoisting arm when the shaft is first rotated for giving an initial upward thrust to the body, the cams being spaced on the shaft so as to confine the winding of the cable to eliminate substantially all lateral stresses on the hoisting arms.

4. A dumping vehicle having, in combination, a dumping body, a pair of hoisting arms for the body each consisting of a single piece of metal bent into a yoke shape with spaced side plates, a shaft, a cable connecting the shaft with each hoisting arm to exert a longitudinal pull on the hoisting arm when the shaft is rotated, a cam roller for each hoisting arm, a pair of cams engaging each cam roller to exert an initial thrust to the body, the cams being spaced on the shaft so as to pass between the side plates of the hoisting arms upon the continued rotation of the shaft, and to confine the winding of the cable to prevent appreciable lateral stresses on the hoisting arms.
